LOCOMOTIVE TENDER

Howard P. Anderson, Erie, Pa., assignor to The Standard Stoker Company, Incorporated, a corporation of Delaware

Application June 24, 1930, Serial No. 463,393
Renewed June 9, 1934

31 Claims. (Cl. 105—234)

This invention relates to railway rolling stock and especially to certain improvements in locomotive tenders for stoker fired locomotives, and it also appertains to improvements in a stoker fuel conveyor for use particularly with the improved locomotive tender.

It has heretofore been the practice to mount the stoker fuel conveyor or its trough portion in a separate compartment formed on the tender between the fuel and water compartments. The fuel conveyor in such installations is driven from gearing at its rearward end disposed at the back of the trough compartment. This arrangement and construction materially reduces the space available for water and complicates the fabrication and maintenance of the tender and of the stoker conveyor.

An object of this invention is to obviate these difficulties and disadvantages of past practice by the provision of a new and improved tender structure and stoker conveyor simplifying fabrication of the tender and at the same time, affording more space for fuel and water, and wherein the stoker trough conveyor is driven from its forward end exteriorly of the tender water compartment.

The coal and water capacity of the tender is a most important factor in the development of new locomotives, and it is highly desirable to obtain the maximum capacity. The design of the tender trucks, bolster and frame determine the lowest point for the bottom of the tender. Clearances of the road, such as tunnels, bridges, switch stands, platforms, etc. determine the height and width of the tender. The length is controlled by the physical characteristics, length of turn tables, and the length of stalls in the engine houses. Thus it will be understood the size of the tender is held within the foregoing well defined limitations. Hence, it is essential all space on the tender be utilized to advantage and as much as possible given over to the fuel and water compartments.

This invention is directed to, as its principal object, the provision of an improved tender structure including stoker mechanism constructed to afford maximum fuel and water space.

Additional objects of the invention will be found in improvements of various parts; in the arrangement and construction of the stoker, and in the structural relation and arrangement of the stoker and the tender as will presently appear from the following description and claims.

On the drawings

Fig. 1 is a central, longitudinal, vertical section

of a locomotive tender, with the improved stoker mechanism applied thereto;

Fig. 2 is a vertical section taken on the line 2—2 of Fig. 5 in the direction of the arrows;

Fig. 3 is a vertical section taken on the line 3—3 of Fig. 5 in the direction of the arrows;

Fig. 4 is a vertical section taken on the line 4—4 of Fig. 5 in the direction of the arrows;

Fig. 5 is a section taken on the line 5—5 of Fig. 2 in the direction of the arrows;

Fig. 6 is a section taken on the line 6—6 of Fig. 4 in the direction of the arrows;

Fig. 7 is a vertical section taken on the line 7—7 of Fig. 1 in the direction of the arrows;

Fig. 8 is an end elevation on the broken line 8—8 of Fig. 1; and

Fig. 9 is a central, longitudinal, vertical section of a portion of a locomotive tender, with a modified form of the improved stoker mechanism applied thereto.

Referring now to the drawings, Figures 1 to 8, illustrate a preferred form of construction selected for the purpose of best describing the invention. Figure 9 shows a modified form of the invention, but it will be evident that other forms may be employed without departing from the spirit of my invention.

The locomotive tender designated generally at A is formed with a fuel compartment B and a water compartment C, and is provided with a fuel conveyor indicated as a whole at D, which conveyor forms a functionally integral part of the tender structure as will presently appear. 10 represents the tender base or frame which comprises the bottom or base plate 11 and an upper plate 12 connected by the ribs 13, and extends from one end of the tender to the other. The base plate 11 is solid, but the upper plate 12 has a series of perforations 14, and the ribs 13 are apertured at 15, so that water can circulate from the water compartment freely in the space between the two plates 11 and 12.

The fuel compartment A is formed by, and separated from the water compartment by partition plates comprising the rear slope sheet 16, the side slope sheets 17 and 18, and the trough member 19 of the fuel conveyor, which trough member in transverse cross section is formed, preferably, of an inverted A shape with the sidewalls 20 and 21 thereof forming substantially straight extended wall portions of the side sheets, 17 and 18. These side sheets and trough sidewalls are securely fastened by riveting, welding or in any suitable manner to form a water tight joint between the fuel and water compartments. Likewise at their 55

rearward ends the trough sidewalls and the solid rear wall 22 of the trough are securely welded to or otherwise suitably arranged with the rear partition plate or slope sheet 16 to form a water tight joint and a rigid tender construction. As best shown in Figures 1, 7 and 9, the rear sheet 16 is extended to the frame to provide a support for the trough member and the fuel compartment. This extended portion is preferably the same width as the transverse supporting plate 23 which together with the lower extended portion of the rear slope sheet serves as water baffles. Any suitable or desired number of such supporting plates may be used as the form of the tender may require.

As can be seen from Figures 1 and 7 particularly the trough member 19 is preferably, though not necessarily, provided in the form of a cast metal integral casting including the centrally and longitudinally apertured cross wall 24 which serves as a floor for the fuel compartment and carries the slidable plates 25 movable longitudinally in the seat portion 26 to provide a shiftable opening 27 through which the fuel enters the trough member.

At its forward end the trough member 19 extends through the water compartment to communicate with a forwardly extending sectional conveyor conduit 30, the rear portion of which is disposed below the trough member and is mounted in a centrally arranged compartment E disposed between the conventional tender bulkheads 31 and 32. The compartment E is formed above the frame 10 and beneath the extended fuel bin floor portion 33. It is bounded at its sides by the bulkheads. The front end is open to receive the conveyor conduit and associated mechanism and is closed at its rear portion by the upstanding transverse wall or partition plate 35 which extends laterally between the sidewalls 36 and 37 of the bulkheads, and vertically between the frame 10 and the trough member 19. The plate 35 is secured to parts named and these parts together with the side slope sheets 17 and 18 are arranged in a manner to form a water tight closure for the water compartment. Figures 1 and 8 clearly illustrate the compartment E and its relation with the remaining tender structure.

It will be seen from Figures 1 and 5 that a firing deck 40 is positioned below the fuel compartment floor portion 33. The distance between the floor and the deck may be varied as desired to meet particular conditions. In this construction less physical effort will be required when hand firing is necessary since the fireman will not be required to stoop when filling the shovel with fuel.

The trough member 19 built in the tender as contemplated by this invention permits utilization of space for water or fuel heretofore wasted. In the construction shown the passage 41 beneath the trough member communicates with the water compartment C as best shown in Figures 1 and 7 to provide communicating water space underneath the partition plates and beneath the trough member. Thus it can be seen that the water compartment extends beneath the fuel trough and all of this space can be used to carry water, or if desired, the construction may be such that this space can be utilized to increase both the fuel and water carrying capacity of the tender in any preferred ratio of one to the other.

A novel fuel advancing conveyor system, including the trough member 19 heretofore described, and a drive arrangement peculiarly ap-

plicable for use with the improved tender of this invention will now be described in detail inasmuch as it is also considered an important feature of the invention. Only that part of the stoker mechanism that advances fuel forwardly from the tender is shown and it will be understood that any form or preferred type of the stoker locomotive unit including distributing means can be used with the tender conveying system of this invention.

The trough member 19 is provided at its forward end with a flange 50, which is suitably secured to the corresponding flange 51 at the rear of the hopper-like casing 52 mounted in the compartment E. The casing 52 is supported from the frame 10 by the legs 53 and 54, which preferably are formed as an integral part of the casing. The upper portion 55 of the casing 52 forms an extension of the trough and is closed at its forward end by a vertical wall 56 forming one of the sidewalls of a gear housing compartment 57, provided with a removable cover 58. The lower portion 59 of the casing 52 extends forwardly beyond the upper portion 55 forming a conduit 60 terminating in a spherical flange 61 adapted to be received in the vertically split coupling member 62 attached to a forwardly extending conduit 63. The portion 59 of the casing 52 is closed at its rearward end by a wall 64 forming one of the sidewalls of a gear housing compartment 65. The gear housing compartment 65 is provided with a cover plate 66, which is shown in the drawings as being an integral part of the trough, though obviously it may be made a separate part. The upper portion 55 of the casing 52 communicates with the lower portion through the opening 67 in its floor. From another aspect of the invention the casing 52 may be considered, and is in effect a hopper-like extension of the conduit 60.

In the trough is a rotatable screw 70 extending into the portion 55 of the casing 52, made up of a plurality of sections suitably connected as by universal joints. This screw is supported in the split bearing 71 at its rearward end and coupled to the shaft 72 at its forward end. The use of a plurality of screw sections permits easy removal and replacement of the conveyor screw. To compensate for the blocks jaw pins etc. at the intersections of the screw sections, the diameter of the screw flights is increased adjacent the intersecting points. At the intersecting points the trough is bulged to accommodate the increase in the diameter of the flights.

The trough is provided with an abutment 73 against which the screw 70 will crush the large lumps of fuel. The screw extends forwardly beyond the abutment into the casing 52 and delivers fuel by gravity through the opening 67 onto the screw 75. The screw 75 is coupled to the shaft 76 at its rearward end and flexibly attached at its forward end to the screw 71, as by a universal joint 78.

The gear driving mechanism for the conveyor system is located at the front end of the tender trough and all gears are in a self-contained casting within the compartment E and entirely without the water compartment. The screw 70 is driven from its forward end by means of the shaft 72. This shaft carries the gear 80 which engages the gear 81 mounted on the forward end of the counter shaft 82. The counter shaft extends rearwardly beneath and to one side of the screw 70 and mounted on its rearward end is a gear 83 which engages the gear 84. The gear 84 mounted

on the shaft 76 in turn engages the gear 85 mounted on the shaft 86. On the same shaft 86 is mounted the gear 87 which engages the gear 88 mounted on the power shaft 89.

- 5 The power shaft can be driven from either end from any suitable prime mover such as by a two cylinder double acting reversible steam engine mounted in the locomotive or if preferred, mounted in the tender directly connected with either 10 end of the power shaft. If the stoker engine is mounted on the tender it would be desirable to enlarge the compartment E by extending it laterally into one of the bulkheads, or extending the compartment further back in the tender.
- 15 In order to protect the trough member 19 from the abrasive action of the screw 70 a removable wear plate 99 is placed in the arcuate shaped portion. This eliminates the necessity of replacing the entire trough member because of frictional wear of the screw and the movement of 20 the fuel.
- 25 All other parts are the same as heretofore described.

Those familiar with tender construction will readily recognize that this invention provides an improved tender and fuel conveyor so constructed 30 and arranged as to utilize all space practically possible for the supply of fuel and water, and that a tender so constructed with all the driving parts for the conveyor mounted exteriorly of the water compartment permits increased tender fuel 35 and water capacities or both in preferred ratios of one to the other.

It is apparent that the trough member may be made either of plates or a cast metal, or that the trough supporting members may be formed integrally with the trough casting, or with the 40 tender frame or both. These and other modifications may be made without departing from the scope of the invention.

I claim:

- 45 1. In combination in a locomotive tender having a base, a body portion including the conventional form and location of bulkheads and comprising fuel and water compartments separated by partition plates, a stoker conveyor extending within said water compartment and opening upwardly to receive fuel from said fuel compartment, and an alcove exteriorly of said water compartment disposed between said bulkheads to receive stoker drive mechanism.
- 50 2. In combination in a locomotive tender having a base, a body portion comprising fuel and water compartments, partition plates separating said compartments, a stoker conveyor disposed within said water compartment and arranged to receive fuel from said fuel compartment, and an alcove exteriorly of said water compartment and apart from the fuel compartment arranged to receive the drive mechanism for said stoker conveyor.
- 55 3. In combination in a locomotive tender having a base, a body portion comprising fuel and water compartments, and means separating said compartments including rear and side sloping partition plates and a separable fuel trough 60 securely attached to the lower marginal portion of said partition plates, said trough comprising an arcuate shaped bottom and outwardly and upwardly diverging straight sidewalls and a transverse wall above said arcuate bottom and extending between and being formed integrally with

said sidewalls, said transverse wall forming a floor for the fuel compartment.

4. As a new article of manufacture a V-shaped stoker trough comprising an integral member having imperforate back and sidewalls and an 5 apertured front wall.

5. As a new article of manufacture an integrally formed stoker trough of an inverted A-shape in transverse cross section and having imperforate back and sidewalls, an apertured front wall, and an apertured transverse wall adapted to form the floor of a tender fuel compartment.

6. As a new article of manufacture an integrally formed stoker trough of an inverted A-shape in transverse cross section, the transverse wall 15 thereof adapted to form the floor of a tender fuel compartment.

7. In a locomotive tender, a fuel bin having inwardly sloping side sheets, and an integrally formed fuel trough of an inverted A-shape in 20 transverse cross section, the transverse wall thereof being apertured to communicate with said fuel bin and forming a floor therefor, and the trough sidewalls being rigidly attached to said side sheets forming a water tight connection therewith. 25

8. In a locomotive tender having fuel and water compartments, the combination of a fuel transferring system including a transfer conduit rigidly mounted on said tender with a rearward portion thereof disposed within the water compartment and with a forward portion located without such compartment, and a second conduit section rigidly mounted on said tender exteriorly of the water compartment communicating with the forward portion of said first named conduit and 35 offset therefrom.

9. In a locomotive tender having fuel and water compartments, the combination of a fuel transferring system including a trough disposed in said water compartment, a conduit section located exteriorly of the water compartment forming a separable extension of said trough, and a second conduit section offset from said first named conduit section and communicating therewith, said trough and conduit sections being rigidly mounted on said tender. 40

10. In a locomotive tender, the combination of a stoker including a screw conveyor on the tender having a gear drive at its forward end only, a second screw conveyor communicating with and 45 extending forwardly from said first named conveyor and having a gear drive mounted at its rearward end on said tender, and a gear shaft and gearing thereon associated with and being interposed between the gear drives of the respective 50 conveyors receiving motion from the gear drive of the second conveyor and imparting motion to the gear drive of said first conveyor, and a power shaft associated with the gear drive of the second conveyor. 55

11. In combination in a locomotive tender having a base, a body portion comprising fuel and water compartments separated by partition plates, a forwardly opening alcove exteriorly of said water compartment formed at the forward 60 end of said tender intermediate the sides thereof, a stoker conduit mounted within said water compartment rearward of the alcove and opening through said water compartment into said alcove, conveying means in said conduit, and mechanism 65 located in said alcove for driving said conveying means from its forward end only.

12. In combination in a locomotive tender having a base, a body portion comprising fuel and water compartments separated by partition plates, 70

18. In combination in a locomotive tender having a base, a body portion comprising fuel and water compartments separated by partition plates, a forwardly opening alcove exteriorly of said water compartment formed at the forward end of 5 said tender, a stoker conduit mounted within said water compartment and having a portion thereof extending forwardly through said water compartment into said alcove, a second stoker conduit mounted on the tender exteriorly of the 10 water compartment and arranged with its rear end portion disposed in said alcove communicating with and offset from that portion of the first named conduit that is likewise disposed in said alcove, conveying means in each of said conduits, 15 a gear drive at the forward end of first named conduit for driving the conveying means thereof and a gear drive at the rearward end of said second named conduit for driving its conveying means, the latter gear drive being disposed rear- 20 ward of the first named gear drive, gearing connecting the first and second named drives for transferring motion from the latter to the former, and a power shaft associated with the sec- 25 ond named gear drive.
19. In combination in a locomotive tender having a base, a body portion including fuel and water compartments, a forwardly opening alcove exteriorly of said water compartment formed at the forward end of said tender, a stoker trough 30 mounted within said water compartment and at its forward end opening forwardly through such compartment into said alcove, a hopper-like member disposed in said alcove and communicating with the open end of said trough, a screw 35 conveyor in said trough delivering fuel into said member, a screw conveyor disposed in the bottom portion of said member for receiving fuel from the first named screw and advancing the same forwardly from said member, the adjacent ends 40 of the screws being offset from one another, a gear drive disposed at the forward side of said member connected with the first named screw conveyor for driving the same from its forward end, a gear drive disposed at the rearward side 45 of said member connected to the second named screw for imparting motion thereto, a power shaft operatively associated with the last named gear drive, and a jackshaft interposed between and associated with the first and second named 50 gear drives for transferring motion from the second named drive to the first named drive.
20. In combination in a locomotive tender having a base, a body portion including fuel and water compartments, a forwardly opening alcove 55 exteriorly of said water compartment formed at the forward end of said tender, a stoker trough mounted within said water compartment and at its forward end opening forwardly through said compartment into said alcove, a hopper-like 60 member disposed in said alcove and communicating with the open end of said trough, a screw conveyor in said trough extending forwardly into said member, a screw conveyor disposed in the bottom portion of said member for receiving fuel 65 from the first named screw and advancing the same forwardly from said member, the adjacent ends of said screws being offset one from the other and the forward end of the first named screw extending forwardly beyond the rearward end of 70 the second named screw, a gear drive disposed at the forward side of said member connected with the first named screw conveyor for driving the same from its forward end, a gear drive disposed at the rearward side of said member connected 75
- a forwardly opening alcove exteriorly of said water compartment and apart from the fuel compartment disposed centrally of the tender at its forward end, a stoker conduit mounted within 5 said water compartment rearward of the alcove and at its forward end portion opening through the front wall of the water compartment into said alcove, conveying means in said conduit, and mechanism disposed in said alcove for driving said conveying means from its forward end only.
13. In combination in a locomotive tender having a base, a body portion comprising fuel and water compartments separated by partition plates, a forwardly opening alcove exteriorly of said water compartment formed at the forward end of said tender intermediate the sides thereof and a stoker conduit mounted within said water compartment rearward of the alcove and having a portion thereof extending forwardly 10 through said water compartment into said alcove.
14. In combination in a locomotive tender having a base, a body portion comprising fuel and water compartments separated by partition plates, a forwardly opening alcove exteriorly of said water compartment formed at the forward end of said tender intermediate the sides thereof, a stoker conduit mounted within said water compartment rearward of the alcove and having a portion thereof extending forwardly 15 through said water compartment into said alcove, and stoker drive mechanism disposed in said alcove.
15. In combination in a locomotive tender having a base, a body portion comprising fuel and water compartments separated by partition plates, a forwardly opening alcove exteriorly of said water compartment and apart from the fuel compartment disposed centrally of the tender at its forward end, and a stoker conduit mounted 20 within said water compartment rearward of the alcove and at its forward end portion opening through the front wall of the water compartment into said alcove.
16. In combination in a locomotive tender having a base, a body portion comprising fuel and water compartments separated by partition plates, a forwardly opening alcove exteriorly of said water compartment formed at the forward end of said tender intermediate the sides thereof, a stoker conduit mounted within said water compartment and having a portion thereof extending forwardly 25 through said water compartment into said alcove, and a second stoker conduit mounted on the tender exteriorly of the water compartment and arranged with its rear end portion disposed in said alcove communicating with and offset from that portion of the first named conduit that is likewise disposed in said alcove.
17. In combination in a locomotive tender having a base, a body portion comprising fuel and water compartments separated by partition plates, a forwardly opening alcove exteriorly of said water compartment formed at the forward end of said tender intermediate the sides thereof, a stoker conduit mounted within said water compartment and having a portion thereof extending forwardly 30 through said water compartment into said alcove, and a second stoker conduit rigidly mounted on the tender exteriorly of the water compartment and arranged with its rear end portion disposed in said alcove communicating with and disposed below that portion of the first named conduit that is likewise disposed in said alcove.

to the second named screw for imparting motion thereto, a power shaft operatively associated with the last named gear drive, and a jackshaft interposed between and associated with the first and second named gear drives for transferring motion from the second named drive to the first named drive.

21. In a locomotive tender, a compartment at its forward end intermediate the sides thereof, a stoker including a screw conveyor, the forward end of said conveyor extending into said compartment, a gear drive in said compartment forward of said conveyor for driving the same from its forward end, a second screw conveyor communicating with said first named screw conveyor and having its rearward end extending into said compartment and disposed in a plane below the forward end of said first named screw conveyor, a gear drive in said compartment disposed rearward of said second named conveyor for driving the same from its rearward end, and means in said compartment interposed between said first named gear drive and said second named gear drive for transferring motion from one to the other.

22. In a locomotive tender, a compartment at its forward end intermediate the sides thereof, a stoker including a screw conveyor, the forward end of said conveyor extending into said compartment, a gear drive in said compartment forward of said conveyor for driving the same from its forward end, a second screw conveyor communicating with said first named screw conveyor and having its rearward end extending into said compartment and disposed in a plane below the forward end of said first named screw conveyor, a gear drive in said compartment disposed rearward of said second named conveyor for driving the same from its rearward end, a power shaft associated with said second named gear drive for imparting motion thereto and means in said compartment interposed between said first named gear drive and said second named gear drive for transferring motion from said second named gear drive to said first named gear drive.

23. In combination, a stoker including a screw conveyor for use in a locomotive tender, a gear drive forward of said conveyor for driving the same from its forward end, a second screw conveyor communicating with said first named screw conveyor and having its rearward end disposed in a plane below the forward end of said first named screw conveyor, a gear drive disposed rearward of said second named screw conveyor for driving the same from its rearward end, a power shaft operatively associated with the second named gear drive and a jackshaft interposed between and associated with the first and second named gear drives for transferring motion from the second named gear drive to the first named gear drive.

24. As a new article of manufacture, an integrally formed stoker trough of an inverted A shape in transverse cross section and having imperforate back and side walls and an apertured transverse wall adapted to form the floor of a tender fuel compartment.

25. In combination, in a locomotive tender having a base, a body portion comprising fuel and water compartments, a forwardly opening alcove exteriorly of said water compartment formed at the forward end of said tender intermediate the sides thereof, a stoker conveyor mounted in said compartment and arranged to deliver fuel toward said alcove, and a second stoker conveyor mounted exteriorly of the water compartment and ar-

ranged with its rear end portion disposed in said alcove communicating with and being offset from the first named stoker conveyor.

26. In combination, a locomotive tender having a base, a body portion including fuel and water compartments, a stoker trough mounted in said water compartment and at its forward end opening forwardly through said compartment, a hopper-like member disposed exteriorly of said water compartment and disposed in communication with the open end of said trough, a screw conveyor in said trough delivering fuel to said member, a screw conveyor disposed in said member for receiving fuel from the first named screw and advancing the same forwardly from said member, the adjacent ends of the screws being offset one from another, a gear drive disposed at the forward side of said member connected with the first named screw conveyor for driving the same from its forward end, a gear drive disposed at the rearward side of said member connected to the second named screw for imparting motion thereto, a power shaft operatively associated with one of said gear drives, and a jack shaft positioned between and associated with the first and second named gear drives for transferring motion from one to the other.

27. In combination in a locomotive tender having a base, a body portion including fuel and water compartments, a stoker trough mounted in said water compartment and at its forward end opening forwardly through said compartment, a hopper-like member disposed exteriorly of the water compartment and being in communication with the open end of said trough, a screw conveyor in said trough extending forwardly into said member, a screw conveyor mounted in said member receiving fuel from the first named screw and advancing the same forwardly from said member, the adjacent ends of the screws being offset one from the other and the forward end of the first named screw extending forwardly beyond the rearward end of the second named screw, a gear drive disposed at the forward side of said member connected with the first named screw conveyor for driving the same from its forward end, a gear drive disposed at the rearward side of said member connected to the second named screw for imparting motion thereto, a power shaft operatively associated with one of said gear drives, and a jack shaft interposed between and associated with the first and second named gear drives for transferring motion one to the other.

28. In combination, a stoker including a screw conveyor for use in a locomotive tender, a gear drive forward of said conveyor for driving the same from its forward end, a second screw conveyor communicating with said first named screw conveyor and having its rearward end disposed in a plane below the forward end of the first named screw conveyor, a gear drive disposed rearward of said second named screw conveyor for driving the same from its rearward end, a power shaft operatively associated with one of said gear drives and a jack shaft interposed between and associated with the first and second named gear drives for transferring motion from one to the other.

29. In combination, a stoker including a screw conveyor for use in a locomotive tender, a gear drive forward of said conveyor for driving the same from its forward end, a second screw conveyor communicating with said first named screw conveyor and having its rearward end disposed in a plane below the forward end of the first named screw conveyor, a gear drive disposed rearward of said second named screw conveyor for driving the same from its rearward end, a power shaft operatively associated with one of said gear drives and a jack shaft interposed between and associated with the first and second named gear drives for transferring motion from one to the other.

- conveyor and having its rearward end offset from the forward end of the first named screw conveyor, a gear drive disposed rearward of said second named screw conveyor for driving the same from its rearward end, a power shaft operatively associated with one of said gear drives and a jack shaft interposed between and associated with the first and second named gear drives for transferring motion from one to the other.
30. In a locomotive tender having a fuel compartment, a fuel transferring system including a fuel receiving conveyor adapted to receive fuel from said compartment, a fuel delivery conveyor receiving fuel from said receiving conveyor and extending forwardly therefrom, said conveyors being rigidly mounted with respect to each other and arranged with the receiving end of the delivery conveyor offset from the delivery end of the receiving conveyor offset from the delivery end of the receiving conveyor, said delivery conveyor at its forward end terminating adjacent the front end of the tender, and a transferring conveyor

movably associated with the forward end of said delivery conveyor and extending therefrom forward of the tender.

31. In a locomotive tender having a fuel compartment, a fuel transferring system including a fuel receiving conveyor adapted to receive fuel from said compartment, a fuel delivery conveyor receiving fuel from said receiving conveyor and extending forwardly therefrom, said conveyors being rigidly mounted with respect to each other 10 and arranged with the receiving end of the delivery conveyor offset from the delivery end of the receiving conveyor, said delivery conveyor at its forward end terminating adjacent the front end of the tender, a transfer conveyor 15 movably associated with the forward end of said delivery conveyor and extending therefrom forward of the tender, said transfer conveyor being driven from said delivery conveyor, and means for driving said receiving and delivery conveyors from 20 their offset ends.

HOWARD P. ANDERSON.
